NOZZLE

Arthur S. Peterson and Carl K. Johnson, Elmwood, Conn., assignors to Anemostat Corporation of America, New York, N. Y., a corporation of Delaware

Application September 13, 1946, Serial No. 696,692

10 Claims. (Cl. 299—142)

1

This invention relates to nozzles of the general type described and claimed in Wallen et al. application, Serial No. 562,027, filed November 4, 1944, and its division, Serial No. 635,855, filed December 19, 1945, now Patent 2,434,340, for directing heated air over window surfaces to remove frost and ice therefrom and to prevent the formation of frost and ice thereon, and has for its general object to provide a nozzle of the said type which is particularly designed for low-cost, facile production and high efficiency in use.

Another object of the invention is to provide a nozzle of the general type referred to which is adjustable to regulate the amount, velocity and direction of air discharged therefrom.

With the foregoing and other objects in view, which will become more fully apparent as the nature of the invention is better understood, the same consists in a nozzle embodying the novel features of construction, combination and arrangement of parts as will be hereinafter more fully described, illustrated in the accompanying drawings and defined in the appended claims.

In the accompanying drawings, where like characters of reference denote corresponding parts in different views:

Fig. 1 is a side elevation of a nozzle constructed in accordance with the invention.

Fig. 2 is an end elevation of the nozzle.

Fig. 3 is a central, longitudinal section through the nozzle.

Fig. 4 is a top plan view of the nozzle.

Figs. 5 and 6 are views similar to Fig. 3 illustrating nozzles of alternative forms.

Fig. 7 is a view similar to Fig. 1 illustrating a nozzle of other alternative form; and

Fig. 8 is a fragmentary view similar to Figs. 3 and 6 illustrating a modification of the nozzle.

Referring to the drawings in detail, first with particular reference to the form of the invention illustrated in Figures 1 to 4, it will be observed that the present nozzle comprises a tubular element A which is open at its rear end for supply of heated air thereto, closed at its front end by a wall 10, and provided in its side wall 11, directly adjacent to its end wall 10, with an arcuate opening 12 for discharge of heated air fan-wise laterally therefrom. It will further be observed that said nozzle comprises a cup-like member B including a side wall 13 and an end wall 14, the former of which is engaged over and is fastened rigidly to the side wall 11 of the tubular element A, as, for example, by means of rivets 15, and the latter of which is disposed in advance of the end wall 10 of said tubular element to provide be-

2

tween said end walls an air space or passageway a.

In the side wall 13 of the cup-like member B, adjacent to the end wall 14 of said member and aligned with the space or passageway a, is an arcuate opening 16 of preferably the same width as said space or passageway a and of any suitable length or angular extent for the admission of ambient air to said space or passageway. Also in the side wall 13 of said cup-like member, adjacent to the end wall 14 thereof and aligned, longitudinally of the nozzle, with the arcuate opening 12 as well as with the space or passageway a, is a second arcuate opening 17 for the outlet of air from said space or passageway a. Preferably the arcuate openings 16 and 17 are disposed diametrically opposite each other.

The tubular element A may comprise the discharge end portion of an air supply duct or, as shown, it may be entirely separate from an air supply duct 18 to which it may be connected in any suitable manner. In any event heated air supplied to said element is delivered therefrom, fan-wise through the arcuate opening 12 and by its flow from the device creates a zone of low pressure in the vicinity of the air outlet opening 17 with the result that flow of ambient air is induced through the space or passageway a. Thus, as long as heated air is discharged from the tubular element A through its arcuate opening 12, ambient air is caused to circulate through the space or passageway a, entering the latter through the inlet opening 16, leaving the same through the outlet opening 17 and becoming intermixed with the heated air whereby the latter is tempered.

The device may be mounted in any suitable manner adjacent to a window of any kind such, for example, as an aircraft cabin window, to deliver air fan-wise over the latter for defrosting, de-icing or ice formation prevention purposes. The heated air may be for cabin heating purposes and may be quite hot, too hot in fact to be directed untempered against certain windows such as those formed of certain plastics or which are laminated. However, because the present device provides for tempering the heated air it provides at the same time, for the use of quite hot cabin heating air for window defrosting and de-icing purposes. It also acts to recirculate the cabin air and thereby tends to maintain the air in the cabin at the same temperature at different locations in the cabin.

The end walls of the tubular element A and the cup-like member B may be of different forms and

may be disposed in different manners relative to the device. For example, said walls may be of conical or inwardly dished form, as shown in Figs. 1 to 4, to avoid turbulence in the tubular element A and to cause the discharged air to flow forwardly as well as laterally outward from the device. Alternatively said walls may be flat or substantially flat and may be disposed at right angles to the longitudinal axis of the device, or they may be flat or substantially flat and may be disposed at inclinations to the longitudinal axis of the device such that the end wall of the tubular element A serves to deflect the heated air supplied through said element toward the air discharge opening therein. This latter arrangement is illustrated in Fig. 5 wherein the tubular element and the cup-like member are designated as A' and B', respectively, and their end walls are designated as 10' and 14' respectively.

These end walls 10' and 14' are shown as being disposed parallel to each other, but if desired only the end wall 10' may be inclined relative to the longitudinal axis of the device and the end wall 14' may be disposed in any desired relationship to said end wall 10' other than parallel thereto. In any event, due to the end wall 10' of the tubular element A' being inclined relative to the longitudinal axis of the device forwardly with respect to the air discharge opening 12' in said element A' the air supplied through said element is deflected by said end wall toward said discharge opening and flows smoothly through the device with little or no turbulence in said element A'.

Instead of the cup-like member being fixed to the tubular element, it may be rotatably mounted on said element to vary the effective lengths of the opening in said element, and the inlet and the outlet openings in said member, thereby to regulate the amount of air discharged from the device and to control its direction of flow therefrom. In this connection, Fig. 6 of the drawing illustrates by way of example that the cup-like member, designated as B², may be connected to the tubular element, designated as A², by a rivet 19 or the like extending centrally through the end walls 14^a and 10^a, respectively, of said member and said element. Thus, the member B² is retained in assembly with the element A² for rotation with respect thereto in either direction to vary the effective lengths of the discharge opening 12^a and of the inlet and outlet openings 16^a and 17^a and the angularity of their effective portions relative to the device to regulate the amount of air discharged from the device as well as to control its direction of flow therefrom. To hold the member B² properly spaced from the element A², a spacing sleeve 20 may be provided on the rivet 19 or the like between the end walls 14^a and 10^a, or any other suitable means may be provided for this purpose.

If desired, the cup-like member may be mounted on the tubular element not only for rotative adjustments with respect thereto, but also for longitudinal adjustment with respect thereto to vary the effective widths of the discharge opening in said element and of the inlet and outlet openings in said member. In this connection, Fig. 7 of the drawings illustrates that the cup-like member, designated as B³ is provided with an arcuate slot 21 and that the tubular element, designated as A³ is provided with a pin 22 disposed in said slot, whereby said member is retained in assembly with said element. The arcuate slot 21, is, however, of sufficient length and width to permit the

cup-like member B³ to be adjusted either rotatably or longitudinally relative to the tubular element A³ sufficiently to completely open or close the air discharge opening 12^c in said element. Thus, opportunity is afforded for varying the effective length and width of said air discharge opening as well as the angularity of its effective length portion relative to the device to control the volume and the direction of flow of air discharged from the device. In this connection it is apparent that by adjusting the member B³ rearwardly to widen the air discharge opening 12^c, the air inlet and outlet openings 16^c, 17^c are narrowed, while by adjusting said member B³ forwardly to narrow the air discharge opening 12^c, the air inlet and outlet openings 16^c and 17^c are widened. Thus, by longitudinal adjustment of the member B³ relative to the element A³, it is possible to temper the discharged air as desired.

According to each of the forms of the invention illustrated in Figs. 1 to 7 of the drawings the peripheral portion of the end wall of the tubular element, between planes which radiate from the axis of said tubular element and which define the angular limits of the discharge opening in said element, is disposed at substantially right angles to the longitudinal axis of the nozzle and extends approximately as far outwardly radially as the inner face of the side wall of the cup-like member. As a consequence, air is discharged from the nozzle at substantially right angles to its longitudinal axis and mixing of the two air streams flowing through the air discharge and the air outlet openings occurs outside of the nozzle. In this connection Fig. 8 illustrates that the peripheral portion of the end wall 10^d of the tubular element A⁴ may, within the aforesaid angular limits of the outlet opening 12^d in said element, be inclined forwardly and may have its edge disposed radially inwardly with respect to the edge of the peripheral portion of the end wall 14^d of the cup-like member B⁴. As a consequence, mixing of the supplied air with the ambient air will take place within, or more or less closely adjacent to, the nozzle and the direction of flow of the mixed air from the nozzle will be more or less forwardly as well as laterally from the nozzle, which may be desirable in certain installations.

According to each of the different forms of the invention the tubular element and the cup-like member are readily capable of being produced and assembled economically and rapidly and therefore the present nozzle is of low production cost.

From the foregoing description considered in connection with the accompanying drawings it is believed that the construction and operation of the present nozzle will be clearly understood and its advantages appreciated. It is desired to point out, however, that while only certain specific embodiments of the invention have been illustrated and described, the same is readily capable of various other specifically different structural embodiments within its spirit and scope as defined in the appended claims.

We claim:

1. A nozzle comprising a tubular element open at its rear end for supply of air thereto and including an end wall closing its front end, said tubular element including a side wall having therein a discharge opening for egress of air from said element, a second end wall disposed in front of and spaced from said first mentioned end wall, and a pair of side walls between said end walls at the peripheries of the latter, said pair of side

walls being disposed in spaced apart relation to each other circumferentially of the nozzle to provide an air inlet opening and an air outlet opening for the space between said end walls, said inlet opening being disposed outside of planes which radiate from the axis of said tubular element and which define the angular limits of said discharge opening, and said outlet opening being disposed at least in part between said planes.

2. A nozzle as set forth in claim 1 in which the end wall of the tubular element is of rearwardly dished form.

3. A nozzle as set forth in claim 1 in which the end wall of the tubular element is substantially flat and is inclined relative to the longitudinal axis of the tubular element forwardly toward the front end air discharge opening in said element.

4. A nozzle comprising a tubular element open at its rear end for supply of air thereto and including an end wall closing its front end, said tubular element including a side wall having therein a discharge opening for egress of air from said element, a cup-like member including both a side wall engaged over the side wall of said tubular element and an end wall disposed in front of and spaced from the front wall of said tubular element, the side wall of said cup-like member having therein an air inlet opening and an air outlet opening for the space between said end walls, said inlet opening being disposed outside of planes which radiate from the axis of said tubular element and which define the angular limits of said discharge opening, and said outlet opening being disposed at least in part between said planes.

5. A nozzle as set forth in claim 4 in which the end wall of the tubular element is of rearwardly dished form.

6. A nozzle comprising a tubular element open at its rear end for supply of air thereto and including an end wall closing its front end, said tubular element including a side wall having therein a discharge opening for egress of air from said element, a cup-like member including both a side wall engaged over the side wall of said tubular element and an end wall disposed in front of and spaced from the front wall of said tubular element, the side wall of said cup-like member having therein an air inlet opening and an air outlet opening for the space between said end walls, and said cup-like member being mounted on said tubular element for rotative adjustment relative thereto to vary the amount of said outlet opening which may be disposed between planes which radiate from the axis of said tubular element and which define the angular limits of said discharge opening.

7. A nozzle comprising a tubular element open at its rear end for supply of air thereto and including an end wall closing its front end, said tubular element including a side wall having therein a discharge opening for egress of air from said element, a cup-like member including both a side wall engaged over the side wall of said tubular element and an end wall disposed in front of and spaced from the front wall of said tubular element, the side wall of said cup-like member having therein an air inlet opening and an air outlet opening for the space between said end walls, said outlet opening being disposed at least in part between planes which radiate from the axis of said tubular element and which define the angular limits of said discharge opening, and

said cup-like member being mounted on said tubular element for longitudinal adjustment relative thereto to vary the effective width of said discharge opening.

8. A nozzle comprising a tubular element open at its rear end for supply of air thereto and including an end wall closing its front end, said tubular element including a side wall having therein a discharge opening for egress of air from said element, a cup-like member including both a side wall engaged over the side wall of said tubular element and an end wall disposed in front of and spaced from the front wall of said tubular element, the side wall of said cup-like member having therein an air inlet opening and an air outlet opening for the space between said end walls, said inlet opening being disposed outside of planes which radiate from the axis of said tubular element and which define the angular limits of said discharge opening, said outlet opening being disposed at least in part between said planes, and said cup-like member being mounted on said tubular element for rotative and longitudinal adjustments relative thereto to vary the effective length and the effective width of said discharge opening and the angularity of its effective portion relative to the axis of the device.

9. A nozzle comprising a tubular element open at its rear end for supply of air thereto and including an end wall closing its front end, said tubular element including a side wall having therein a discharge opening for egress of air from said element, a second end wall disposed in front of and spaced from said first mentioned end wall, and a pair of side walls between said end walls at the peripheries of the latter, said pair of side walls being disposed in spaced apart relationship to each other circumferentially of the nozzle to provide an air inlet opening and an air outlet opening for the space between said end walls, said inlet opening being disposed outside of planes which radiate from the axis of said tubular element and which define the angular limits of said discharge opening, said outlet opening being disposed at least in part between said planes, the peripheral portion of the end wall of said tubular element within the angular limits of the outlet opening in said element having its outer edge disposed radially inwardly with respect to the outer edge of said second mentioned end wall.

10. A nozzle comprising a tubular element open at its rear end for supply of air thereto and including an end wall closing its front end, said tubular element including a side wall having therein a discharge opening for egress of air from said element, a second end wall disposed in front of and spaced from said first mentioned end wall, and a pair of side walls between said end walls at the peripheries of the latter, said pair of side walls being disposed in spaced apart relationship to each other circumferentially of the nozzle to provide an air inlet opening and an air outlet opening for the space between said end walls, said inlet opening being disposed outside of planes which radiate from the axis of said tubular element and which define the angular limits of said discharge opening, said outlet opening being disposed at least in part between said planes, the peripheral portion of the end wall of said tubular element within the angular limits of the discharge opening in said element being inclined forwardly and outwardly relative to the longitudinal axis of the nozzle toward the front

end of said discharge opening and having its outer edge disposed radially inwardly with respect to the outer edge of said second mentioned end wall.
